GARMENT HANGER

Swen Boe and Joseph B. Hanson,
Minneapolis, Minn.

Application December 21, 1942, Serial No. 469,611

3 Claims. (Cl. 223—95)

This invention provides an extremely simple and highly efficient garment hanger capable of use either as a skirt hanger or a hanger for men's trousers and, generally stated, consists of the novel devices, combinations of devices, and arrangement of parts hereinafter described and defined in the claims.

As is well known, the government, for war purposes, has appropriated to a very great extent metals such as iron and steel, from which garment hangers have hitherto quite generally been made. This invention provides a readily adjustable, durable and efficient garment hanger that may be made entirely from wood or from non-metallic material such as Bakelite or other phenol condensation products.

Several forms of the invention are illustrated in the accompanying drawings wherein like characters indicate like parts throughout the several views.

Referring to the drawings:

Fig. 1 is a side elevation, with some parts sectioned, showing a form of the device especially designed for use as a skirt hanger, the latter being indicated partly in side elevation and partly in section;

Fig. 2 is a side elevation of the skirt hanger shown in Fig. 1, some parts being broken away and the skirt being removed;

Fig. 3 is a view corresponding to Fig. 1 but showing the device in a shorter form especially designed for use as a hanger for men's trousers and showing the device applied to hold a pair of trousers;

Fig. 4 is a horizontal section taken on the line 4—4 of Fig. 3;

Fig. 5 is a fragmentary section taken on the line 5—5 of Fig. 3; and

Fig. 6 is a side elevation showing a form of the hanger made from plastic material such as stated.

Referring first to the hanger shown in Figs. 1 and 2, the numeral 10 indicates a pair of normally straight flexible rods preferably made from wood, preferably hard maple or birch. The numerals 11 and 12 indicate rod-like wooden garment clamping legs, and the numeral 13 indicates a rod-like wooden hanger forming post, which latter has a laterally and obliquely projecting pin 14. The relatively fixed leg 11, at its upper portion, has parallel holes 15 through which the rods 10, at one end, are passed with quite tight engagement. The leg 12 has parallel transverse holes 16 through which the other ends of the rods 10 are passed with normally quite loose engagement so that said leg can be slid

on the rods to give spaced adjustment to the legs. The holes 15 are oblique to the axis of the leg 11 and the holes 16 are oblique to the axis of the leg 12. This causes the legs 11 and 12 to downwardly diverge so that they will have a better holding action on the skirt indicated by the character *a*. The lower end of the hook forming post 13 has parallel holes 17 that are parallel to each other but oblique to the axis of said post and through which holes the intermediate or central portions of the rods 10 are passed with quite close fitting engagement. The holes 17 are much closer together than are the holes 15 and as are the holes 16. When the rods are thus forced through the legs 11 and 12 and posts 13, their central portions will be slightly bowed or drawn together, thereby increasing the frictional clamping action between the leg 12 and rods, between the leg 12 and the rods, and between the post 13 and the rods.

With this arrangement the leg 12 will be quite freely slideable on the rods but the leg 11 and post 13 will be held against free sliding movement on the rods but may be slid thereon when considerable force is applied thereto. The adjustment of the leg 12 with respect to the leg 11 will adjust the device for various widths of garment skirt waists. In applying this hanger to a skirt, the leg 12 will be slid until it puts the garment waist under some tension and the tension of the waist on these legs will increase the frictional clamping action between the rods and the leg 12, thereby preventing accidental contraction of the garment hanger. The divergence of the legs 11 and 12 and the tension that the garment is put under will hold the latter securely against dropping from the hanger. The hanger hook forming elements 13 and 14 afford a very efficient hanger hook.

The so-called trouser hanger illustrated in Figs. 3, 4 and 5 involves elements that correspond to the elements in the so-called skirt hanger, that is, it includes the rods 10a, legs 11a and 12a, and the hanger hook forming elements 13a and 14a. However, in this form of the device the legs 11a and 12a, at their lower ends, are split or bifurcated at 18 so that the folds of the two legs of the garment, indicated at *b*, may be inserted in the said slots. Also to assist in holding the trousers against dropping from the legs 11a and 12a, their inner surfaces are notched or serrated at 19. Obviously, the manner of applying the trouser hanger to the trousers *b* is similar to that of applying the skirt hanger to a skirt, except that the trousers are to be turned upside-

down and hung from their normally lower ends.

In the modified form of the hanger shown in Fig. 6, the rods 20 are shown as formed or cast integral with a body member 21 having an integrally formed hanger hook 22. The relatively fixed depending garment engaging leg 23 is shown as cast integral with the body 21 and the relatively movable leg 24 is shown as provided with holes through which the free ends of the rods 20 are slid under frictional contact. In all of the forms of the device illustrated, the adjustment of the hanger to a garment will be under some tension which will frictionally hold the movable leg against accidental sliding movements on the rods. As to the structure illustrated in Fig. 6, the rods 20 might be wooden rods, the ends of which might be cast into the body member 21. Also the rods 20 might be of plastic material inserted into and cemented or otherwise secured to the body member 21.

In all of the forms of the hanger illustrated, the tension on the lower portion of the movable leg, when the garment is applied, increases the frictional biting action of the upper portion of the leg on the rods.

Several forms of the hanger are illustrated but it will be understood that other modifications thereof may be made within the scope and spirit of the invention herein disclosed and claimed.

What is claimed is:

1. A garment hanger including a pair of spaced flexible rods and a pair of depending garment-engaging legs applied over the end of said rods, said legs having holes through which said rods are passed, one of said legs being capable of sliding movements on said rods but having a fric-

tional biting or clamping action on the rods when a garment is applied to the depending portions of said legs, and a hanger hook forming element located intermediate said legs and having holes 5 through which the intermediate portions of said rods are passed, said rods outwardly of said hook-forming element being connected only by said legs.

2. A garment hanger including a pair of spaced rods and a pair of depending garment-engaging legs applied to the ends of said rods, said legs having holes through which said rods are passed, one of said legs being capable of sliding movements on said rods but having a frictional biting or clamping action on the rods when a garment 15 is applied to the depending portions of said legs, and a hanger hook forming element involving a post-like portion having holes through which the intermediate portions of said rods are passed, 20 the holes in said hanger hook forming element being closer together than the holes in said legs, thereby holding the intermediate portions of said rods closer together than the end portions thereof and increasing the biting action between said rods and the relatively movable leg.

3. The structure defined in claim 1 in which the holes in said hanger hook-forming element are closer together than the rod-receiving holes in said legs, whereby said rods will diverge outwardly from the intermediate hook-forming element to a variable extent depending upon the spacing of said legs from the hook-forming ele-
